DEEP WELL PUMP

William L. Connor, Los Angeles, Calif., assignor
to Fluid Packed Pump Company, Whittier,
Calif., a corporation of Nevada

Application October 14, 1935, Serial No. 44,818

8 Claims. (Cl. 103—187)

My invention relates to reciprocating pumps, and is directed to a pump construction especially applicable to deep well installation.

The principal object of my invention is to provide a pump that will deliver an exceptionally large quantity of fluid for a given length of stroke.

The engineer attacking the problem of adequate pumping from the exceedingly deep wells that are becoming more numerous in current oil production, is confronted by at least four important limiting considerations. These considerations should be given some thought for a proper understanding of the present invention.

First, there is the fact that the cross-sectional area of an oil pump must be confined to the dimensions of the discharge tubing, which, in turn, must be accommodated by the well casing. Of necessity, therefore, the pump itself may be no larger than two or three inches in diameter.

Secondly, the usual power equipment installed at a well provides for a limited length of pump stroke, partly from custom and standards established in pumping wells of moderate depth, and partly because of the greater investment and high operating cost involved in using equipment for longer pump strokes. The power required to lift the long column of oil in a deep well taxes standard equipment; to increase the amplitude of the pump stroke without reducing the number of strokes per minute may further tax prevailing power equipment as to be impractical, or, at best, to involve serious offsetting losses. For example, it must be borne in mind that increasing the throw of a pump crank increases the acceleration and velocity of the long oil column and string of rods.

The third important consideration is that because of the inordinate weight of the oil column in a deep well, and because of the excessive distance separating the power unit from the pump, resiliency of the string of rods becomes a serious loss factor. This stretch in the pump rods is subtracted from the power stroke at the surface to net the effective stroke at the pump.

Finally, increasing the number of strokes per minute has serious disadvantages. In current practice, it is common, because of the stretch in the rods at a great depth, to use a relatively small pump at a compensating relatively high number of strokes per minute. Two cost factors enter here. In the first place, the more rapidly a pump operates for a given rate of production, the more wear and the higher the ratio of cost of pump replacement to production. In the second place,

the greater the number of times the string of rods must be stretched for a given quantity of production, the greater the waste of power.

The advantages of my invention may be readily understood in the light of the four considerations recited. By providing for increased volume of oil flow per unit length of pump stroke, within the restricted cross-sectional area of well tubing, I compensate for motion lost in the stretch of the rods, and do so without engendering difficulties inherent either in increasing the length of the strokes, or in increasing the rate of the strokes. Standard power equipment may be utilized at customary speeds, and pump replacement will be normal for any given well.

I accomplish increased pump capacity by incorporating two pumping units in tandem in a single pump structure, arranging for one of the pumping units to pump into or through the other pumping unit.

Broadly described, my invention comprises two pump cylinders in telescopic relation adapted for relative movement longitudinally, each cylinder carrying a piston that is effective with the other cylinder, a fluid passage being provided to permit one cylinder to pump either into or through the other cylinder.

The recital of other objects, advantages and features of my invention is, for the purpose of better understanding, reserved for the detailed description to follow. In this disclosure, the principles of my invention are, for illustration, embodied in a removable type pump.

In the accompanying drawings:

Fig. 1 is a broken elevation, largely in section, of my pump installed in a well tubing;

Figs. 2, 3, and 4, taken together, comprise an enlarged axial section similar to Fig. 1;

Fig. 5 is a horizontal section taken on line 5—5 of Fig. 3;

Fig. 6 is a horizontal section taken on line 6—6 of Fig. 3;

Fig. 7 is a fragmentary axial section indicating a modified construction wherein one of the pump valves is omitted; and

Fig. 8 is a fragmentary axial section indicating how my invention may be modified by adding a bottom discharge valve.

Pump jacket 10 is incorporated in the usual discharge tubing through which oil is pumped to the surface of the well. Threaded to the bottom of the jacket, as an extension thereof, is standing valve shoe 11, which has the usual tapered seat 12 and inwardly disposed annular shoulder 13. From the bottom of the standing

valve shoe, a gas anchor plug 14 and further tubing (not shown) may extend if required.

Under normal pumping conditions, an expansion mandrel 15 is removably seated in standing 5 valve shoe 11. Shoulders 16 on flexible extensions 17 of the mandrel engage the aforementioned annular shoulder 13 of the standing valve shoe.

Expansion mandrel 15 supports the stationary 10 parts of my pump, including a lower standing valve generally designated 18, a lower and outer cylinder 19, and a tube or small cylinder 20; while the movable parts of the pump, including an inner and upper cylinder 21, are supported 15 and moved by sucker rod 22.

It will be noted that mandrel 15, together with standing valve shoe 11, forms a seal between, on the one hand, the well-pressure zone below the pump and outside the pump jacket, and, on 20 the other hand, the tubing-pressure zone within the jacket that is subject to the tremendous weight of the oil column extending to the top of the well.

Standing valve cage 23 is in the form of a 25 coupling in threaded engagement with expansion mandrel 15, and, in the usual manner, is provided with ball guides 23a. Suitably secured between cooperating surfaces of the expansion mandrel and the valve cage is a valve seat 24 30 to receive ball 25. The range of the ball upward is limited by a suitable diametric stop 26, the stop being integral with a nipple 27 threaded into the upper end of valve cage 23. The upper portion of nipple 27 is reduced in diameter and 35 threaded to receive a spider generally designated by numeral 28, and is further reduced at its upper extremity 27a and cut away to provide a plurality of radially disposed ports 29.

Spider 28 comprises a lower tubular portion 30 40 threaded on its inner and outer peripheral surfaces, a plurality of integral legs 31, and an integral, upper, restricted ring-portion 32. The outer threads of the spider provide convenient means for mounting lower and outer cylinder 19 45 to expansion mandrel 15.

Tube 20 is provided at the bottom with an integral annular shoulder 33 and is dimensioned to fit through ring 32 with shoulder 33 engaging the ring from below, with the weight of the tube 50 on the upper end of nipple 27. A liberal clearance is provided between the periphery of the tube and ring 32 and also between annular shoulder 33 and the legs 31 of the spider. By virtue of this arrangement, the tube is secured 55 against longitudinal movement but has a substantial degree of lateral freedom.

It will be apparent that the interior of tube 20 is in communication with passage 34 leading 60 upward from standing valve 18 and also, by virtue of ports 29 and the spaces between the legs of the spider, is in communication with an annular pump chamber 35 between the tube and outer cylinder 19.

Mounted to the top of tube 20 by threaded engagement is a relatively extensive, annular piston 36 (Fig. 2) dimensioned to cooperate with travelling inner cylinder 21 for pumping action.

In the preferred form of my invention, this 70 piston serves as an extension of tube 20 and is provided with an upper standing valve generally designated by numeral 37. In the drawings, valve cage 38, threaded to piston 36 as an extension thereof, is provided with the usual ball guides 39 and stop pin 40, and cooperates 75

with the upper end of the piston to secure a valve seat 41 for receiving ball 42.

Threaded to the lower end of sucker rod 22 is valve cage 43 of an upper travelling valve 5 that is generally designated by numeral 44. The valve cage is provided with ports 45 communicating with the tubing-pressure zone exterior of the pump. Secured between cooperating surfaces of the valve cage and a nipple 46 that is threaded to the cage, is a valve seat 47 to receive ball 48. Nipple 46 in turn supports, by threaded engagement, the aforementioned inner cylinder 21.

Mounted to the lower end of inner cylinder 21 by threaded engagement is a relatively, extensive, 15 annular, travelling piston 49 dimensioned to cooperate both with tube 20 and with outer cylinder 19 for pumping action. The purpose of the lateral freedom of the bottom of the tube will now be apparent: by virtue of the clearance provided, the tube will automatically adjust itself to any inaccuracy in the boring and machining of the travelling piston.

Annular space 50, defined by tube 20, travelling cylinder 21, and the two pistons, expands 25 and contracts with the action of the pump. It is essential that this space be vented to the tubing-pressure zone exterior of the pump. For this purpose, the wall of travelling cylinder 21 30 may be provided with suitable vent ports 51 near the top edge of travelling piston 49, and around the above these ports the outer surface 35 of the inner travelling cylinder may be either cut away longitudinally or reduced in diameter for a sufficient longitudinal distance to extend above the top edge of standing cylinder 19, thereby providing a clearance space 52 open at all times between the inner travelling cylinder and the outer standing cylinder.

It is contemplated that in a typical pump, 40 each of the two pistons will be approximately three feet long, and that the pump will be dimensioned for approximately a six-foot stroke.

The drawings indicate the disposition of the various parts of the pump at or near the bottom 45 of the stroke. As sucker rod 22 lifts inner travelling cylinder 21 on the upward stroke of the pump, travelling valve 44 will close under pressure from the oil column in the well tubing. As travelling valve 44 retreats from stationary piston 36, pump chamber 53 in the travelling cylinder will expand; and as travelling piston 49 simultaneously retreats from the bottom end of standing cylinder 19, annular pump chamber 35 50 will likewise expand. On this movement, pressure from the well will open lower standing valve 18, and oil from below the pump under well pressure will flow into upper pump chamber 53 55 through tube 20, opening valve 37, and oil likewise will flow through ports 29 and between legs 60 31 of the spider into lower annular pump chamber 35.

On this upward movement of the pump, annular space 50 will contract, the oil therefrom escaping freely into the tubing-pressure zone by 65 virtue of ports 51 and clearance space 52.

As travelling piston 49 approaches stationary piston 36, the stationary piston cuts off ports 51, thereby restricting flow from annular space 50 to produce a cushioning effect at the top of the 70 stroke.

On the downward stroke, standing valve 18 will close; oil from annular pump chamber 35 will be expelled between the legs of the spider through ports 29 and up tube 20 past valve 37 75

into upper pump chamber 53; and oil from chamber 53, forcing open travelling valve 44, will be discharged into the well tubing.

On this downward stroke, annular space 50, expanding in volume, will receive oil freely from the tubing-pressure zone.

My pump may be regarded as consisting of two inter-connecting pumping units: the upper pumping unit, represented by chamber 53, comprises travelling cylinder 21, travelling valve 44, and stationary piston 36; the lower pumping unit, represented by annular chamber 35, comprises standing cylinder 19, the exterior of tube 20, travelling piston 49, and lower standing valve 18.

It will be noted that it is possible for me, in effect, to arrange two pumps in tandem to operate within the confines of well tubing, because, by virtue of tube 20, I provide for communication between the two pumps, so that, on the intake stroke, the upper pump may draw from the lower pump or through the lower pump, and on the discharge stroke, the lower pump will be permitted to deliver fluid to the upper pump.

Regarded in one aspect, tube 20 on the intake stroke of the pump is merely an inflow passage from the well-pressure zone, the tube being, in effect, a by-pass from the well-pressure zone to the upper pumping unit, the by-pass extending through the lower pump, rather than around it, for economy of space and simplicity of construction. Oil entering the intake port of the pump, i. e., lower standing valve 18, may divide, in effect, into two streams, one stream entering the lower pump and the other stream continuing up tube 20 to the upper pump, in which case, the tube functions as a by-pass; or, on the other hand, the entire stream that flows through the lower standing valve may pass into the lower pump, so that the upper pump merely draws from the body of oil in the lower pump. Which of these two conditions exists depends upon the relative size and disposition of ports 29.

In the construction shown in Figs. 1-6, the term "by-pass" applied to tube 20 is most apt; but if, as indicated in Fig. 8, the bottom of the tube is sealed with a plug 54 and the tubing wall is apertured to provide ports 55, all of the oil entering the tube would first flow into pump chamber 35, so that, on the intake stroke of the pump, the tube would be regarded simply as a channel of communication between the two pump chambers, rather than as a by-pass independent of lower pump chamber 35.

In either construction, on the downward discharge stroke of the pump, tube 20 serves simply as a means for conveying oil from the lower pump to the upper pump, and the by-pass aspect does not appear.

Because two pumping units are provided in tandem and connected to the same sucker rod for simultaneous operation, my pump will deliver a greater volume of fluid per unit length of stroke than any other reciprocating pump heretofore employed in deep wells. A simple plunger pump of the same inside diameter as the outer standing cylinder would deliver, in one stroke, a volume of oil equal to the length of the stroke times the cross-sectional area of the standing cylinder; whereas my pump will deliver the same volume plus the stroke times the cross-sectional area of annular pump chamber 35.

Provided the well produces enough oil to work the pump at capacity, on the down stroke, when standing valve 18 is closed, the column of oil in

the tubing-pressure zone will remain substantially stationary while the moving parts of the pump slip through the fluid, the fluid escaping from the pump through travelling valve 44. On the up stroke of the pump, when travelling valve 44 is closed, the pump moving upward displaces in the tubing around the pump a volume equal to the volume of oil previously discharged from the pump on the down stroke, such displacement causing the oil column to move towards the surface of the well.

In pumping to capacity fluid that is relatively free of gas, upper standing valve 37 will remain open substantially all the time, because, on the upward stroke, the upper pumping unit will be expanding to receive oil through tube 20, and, on the downward stroke, the lower pumping unit will be contracting to expel oil through tube 20 in the same direction. It is apparent, then, that this intermediate valve, upper standing valve 37, may be omitted entirely.

The two pumping units are essentially pulsating chambers, and annular space 50 is a third or intermediate pulsating chamber that discharges alternately with the two pumping units. This third pulsating chamber is, of course, not an effective pumping unit in the sense of contributing directly to the capacity of the pump by adding its volume to that of the two pumping units, since it merely draws fluid from the tubing-pressure zone and then returns that fluid. By arranging for free passage of fluid to and from this annular space, I provide continuous pressure therein, direct from the exterior of the pump, to discourage any tendency of fluid to seep by the pistons to this third pulsating chamber from either of the two pumping units. Such alternating flow between the third pulsating chamber and either of the two pumping units would detract from the capacity of the pump and might be sufficient to reduce the total capacity to that of a simple single-acting pump. A virtue, then, of free communication in both directions between annular space 50 and the exterior of the pump is that it tends to keep the pump functioning at full potential capacity.

One modification of my pump consists simply in omitting this valve, as indicated by Fig. 7, in which corresponding parts are given corresponding numbers. In that figure, stationary piston 36a is shown with an unimpeded passage.

While this intermediate valve may be omitted, I prefer to include it for two reasons: first, because it is believed that, where a high ratio of gas to fluid is being pumped, the valve may serve to break up the gas column within the pump and thereby facilitate compression of the gas for discharge from the pump; secondly, because by providing three valves, I have a pump that will continue to function when any one of the three valves fails. If the intermediate valve fails to close, the volume delivered by the pump will not ordinarily be affected; if the upper or travelling valve fails to close, the lower pumping unit will continue to function; if the lower standing valve fails to close, the upper pumping unit will continue to function.

A second modification of my invention, as indicated by Fig. 8, corresponding numbers being used to indicate corresponding parts, is distinguished by the addition to the lower pumping unit of a bottom discharge valve generally designated by numeral 56.

In this third form of my invention, a plain nipple 57, having valve stop 58, is threaded into

the top of standing valve cage 23. Threaded to the top of nipple 57 is a tubular section 59. Threaded, in turn, to the top of tubular section 59 is a nipple 60 that has a reduced upper portion 61 threaded to receive spider 28 and a further reduced upper extremity 61a cut away to provide ports 62. Tube 20a, resting on nipple 61, has, as noted previously, plug 54 and peripheral ports 55. Standing cylinder 19 is threaded to the base 10 of spider 28.

Lower discharge valve 56 comprises a T shaped tube 63, spanning tubular section 59, the horizontal portion of the tube, forming two ports 64 in the periphery of tubular section 59. A suitable bushing 65 screwed into the bottom of vertical portion 66 of the T secures in place a valve seat 67 that is adapted to receive ball 68. A suitable depending lug 69 within the T serves as a stop for ball 68.

On the upward stroke of the pump, this third form of my invention functions in the same manner as the first two forms, lower discharge valve 56 being closed. On the down stroke of the pump, however, fluid from the lower pumping unit may be discharged entirely through valve 56, each pumping unit discharging independently of the other. Obviously, in that case, oil would flow through tube 20 only on the up stroke of the pump.

In the removable type of deep well pump here shown, the pump is removed by simply drawing sucker rod 22 upward beyond the usual range of the pump stroke, until travelling piston 49 engages stationary piston 36. The force upward exerted by the sucker rod will then be transmitted to the stationary parts of the pump through tube 20, and expansion mandrel 15 may readily be jarred out of engagement with shoulder 16 of standing valve shoe 11. The pump assembly may then be readily lifted to the surface of the well.

It is apparent, then, that, while it is desirable to restrict the cross-sectional area of tube 20 for the purpose of increasing the cross-sectional area of annular pump chamber 35 to attain maximum pump capacity, the limit to which the cross-sectional area of tube 20 may be restricted will be determined by two considerations: the fact that the tube must be large enough to accommodate, without serious friction, the required flow of fluid through the tube; and the fact that the tube itself must be of sufficient size and strength to accommodate strain incidental to disengaging the pump from the standing valve shoe and transporting the pump to the surface of the well. Because of this latter consideration, I prefer to use alloy steel for tube 20.

Restricting the cross-sectional area of tube 20 reduces the residual volume of the pump, i. e., the cubical content of the pump at the end of the discharge stroke. When the residual volume of a pump is relatively large, the efficiency of the pump may be seriously impaired by the presence of excessive gas in the oil; because the work of the pump will be devoted largely to merely compressing the gas within the pump. It is believed that my pump has less residual volume than any other pump of the same size employing telescoping pump cylinders. Since my pump expands on the intake stroke to a relatively large volume, and since the efficiency of a pump in the presence of gas is favored by a high ratio between this expanded volume and the residual volume, my invention may be used profitably where the presence of a large per-

centage of gas in a deep well would preclude economic operation of another type of pump.

For the purposes of complete disclosure and to illustrate the principles involved, I have described my invention as embodied in a deep well pump of the removable type. It is obvious that the invention may be applied to pumps of other types for other purposes. It will also be apparent that my invention may be subject to a wide range of material modification and change without departing from the principles involved. I reserve the right to all such modification and change that come within the scope of my appended claims. For instance, a reversed form suggested by the present disclosure is shown and described in my co-pending application, serially numbered 44,819, filed on the same date, and likewise entitled "Deep well pump".

Having described my invention, I claim:

1. A pump having in combination: an inner tube and an outer cylinder concentrically arranged and spaced from each other to form an annular space therebetween, said tube and cylinder being joined together by a fluid-tight connection adjacent the lower end of the outer cylinder; a non-return, valve-controlled inlet port adjacent the lower end of the outer cylinder; a constantly open port in the inner tube adjacent its lower end, above the inlet port, communicating with said annular space; a plunger comprising a cylindrical member telescopically arranged between said inner tube and outer cylinder; a non-return, valve-controlled discharge port in said plunger; a non-return valve controlled discharge port adjacent the lower end of the outer cylinder intermediate the inlet port and said constantly open port in the inner tube; an annular piston on the inner tube to cooperate with the plunger for pumping action; and a second annular piston on the plunger to slidely engage the inner tube and the outer cylinder for pumping action, said pistons isolating the annular space therebetween, which increases and decreases in volume upon reciprocation of the plunger, the plunger being provided with a constantly open port venting said otherwise isolated annular space to the exterior of the pump. 30

2. A pump having in combination: an inner tube and an outer cylinder concentrically arranged and spaced from each other to form an annular space therebetween, said tube and cylinder being joined together by a fluid-tight connection adjacent the lower end of the outer cylinder; a non-return, valve-controlled inlet port adjacent the lower end of the outer cylinder; a check valve associated with the inner tube to prevent downward flow therethrough; a constantly open port in the inner tube adjacent its lower end, above the inlet port, communicating with said annular space; a plunger comprising a cylindrical member telescopically arranged between said inner tube and outer cylinder; a non-return, valve-controlled discharge port in said plunger; a non-return valve controlled discharge port adjacent the lower end of the outer cylinder intermediate the inlet port and said constantly open port in the inner tube; an annular piston on the inner tube to cooperate with the plunger for pumping action; and a second annular piston on the plunger to slidely engage the inner tube and the outer cylinder for pumping action, said pistons isolating the annular space therebetween, which increases and decreases in volume upon reciprocation of the plunger, the plunger being provided with a constantly open port vent- 40

ing said otherwise isolated annular space to the exterior of the pump.

3. A pump having in combination: an inner tube and an outer cylinder concentrically arranged and spaced from each other to form an annular space therebetween; a fluid-tight wall connecting said tube and cylinder adjacent their lower ends, sealing the lower end of the annular space; an inlet port through said wall leading to the inner tube; an upwardly opening non-return valve for said port; a constantly open port in the inner tube adjacent its lower end, above the inlet port, communicating with said annular space; a plunger comprising a cylindrical member telescopically arranged between said inner tube and outer cylinder of slightly less outer diameter than the inner diameter of the outer cylinder; a non-return valve controlled discharge port adjacent the lower end of the outer cylinder intermediate the inlet port and said constantly open port in the inner tube; an annular piston on the inner tube adapted to operate with the plunger for pumping action; and a second annular piston on the plunger to slidably engage the inner tube and the outer cylinder for pumping action, said pistons isolating the annular space therebetween, which increases and decreases in volume upon reciprocation of the plunger, the plunger being provided with a constantly open port, above its piston, venting the otherwise isolated annular space laterally through the side of the plunger to the space intermediate the plunger wall and the outer cylinder.

35. 4. A duplex pump for wells, a tubing in which the pump is positioned comprising a stationary barrel, a standing valve mounted in the stationary barrel adjacent the lower end thereof, a stationary piston, a conduit extending from adjacent the standing valve through the stationary piston, a traveling barrel within the stationary barrel, said traveling barrel extending over the stationary piston, a traveling piston mounted on the traveling barrel, said piston surrounding said conduit, there being a pumping chamber above the stationary piston and in the traveling barrel, a second pumping chamber below the traveling piston and in the stationary barrel, a check valve mounted at the upper end of the traveling barrel and sucker rod connecting means on the traveling barrel, a bottom discharge valve mounted in the stationary barrel above the standing valve and below the lower pumping chamber, said bottom discharge valve opening into the tubing whereby liquid from the bottom pumping chamber is discharged through said bottom discharge valve into the tubing, and closure means between the tubing and the stationary barrel, said closure means being arranged below the bottom discharge valve.

50. 5. A duplex pump for wells, a tubing in which the pump is positioned comprising a standing valve, a stationary barrel mounted on the standing valve and rising therefrom, a pull tube mounted on the standing valve and rising therefrom, a traveling barrel positioned within the stationary barrel, a check valve mounted on the upper end of the traveling barrel, sucker rod coupling means on the traveling barrel, a traveling piston mounted on the traveling barrel, a stationary piston mounted on the upper end of the pull tube, said piston being positioned within the traveling barrel, the traveling piston encircling the pull tube and operating in the stationary barrel, said pump having an upper pumping

chamber above the stationary piston, a lower pumping chamber below the traveling piston, both of said chambers simultaneously drawing the liquid through the standing valve and simultaneously discharging liquid through the valve on the upper end of the traveling barrel, and a bottom discharge valve in the stationary barrel and above the standing valve, said bottom discharge valve having ports opening into the tubing, said bottom discharge valve being adapted and arranged to discharge the liquid from the lower pumping chamber into the tubing, and closure means between the tubing and the stationary barrel, said closure means being arranged below the bottom discharge valve.

15. 6. A duplex pump for wells, a tubing in which the pump is positioned comprising a standing valve, a stationary barrel mounted on the standing valve and rising therefrom, a pull tube mounted on the standing valve and rising therefrom, a traveling barrel positioned within the stationary barrel, a check valve mounted on the upper end of the traveling barrel, sucker rod coupling means on the traveling barrel, a traveling piston mounted on the traveling barrel, a stationary piston mounted on the upper end of the pull tube, said piston being positioned within the traveling barrel, the traveling piston encircling the pull tube and operating in the stationary barrel, said pump having an upper pumping chamber above the stationary piston, a lower pumping chamber below the traveling piston, both of said chambers simultaneously drawing the liquid through the standing valve and simultaneously discharging liquid through the valve on the upper end of the traveling barrel, a lock- 20 ing shoe depending from the standing valve, said locking shoe being releasably held in the tubing, a valve mounted in the stationary piston, and a bottom discharge valve in the stationary barrel and above the standing valve, said bottom discharge valve being adapted and arranged to discharge the liquid from the lower pumping chamber into the tubing, and closure means between the tubing and the stationary barrel, said closure means being arranged below the bottom discharge valve.

25. 7. A duplex pump for wells, a tubing in which the pump is positioned comprising a standing valve, a locking shoe depending from the standing valve, said locking shoe being releasably held in the tubing, a bottom discharge valve housing fixedly mounted on the standing valve and arranged above said standing valve, a valve in said housing, said housing having ports opening into the tubing, said valve controlling the flow from within the pump to said ports, a stationary barrel mounted on the standing valve and rising therefrom, a stationary pull tube mounted on said housing and rising therefrom, a stationary piston mounted on the upper end of the pull tube, a traveling barrel extending over the stationary piston and arranged within the stationary barrel, a traveling piston mounted on the lower end of the traveling barrel, said traveling piston surrounding the pull tube, said pump having a lower pumping chamber below the traveling piston and within the stationary barrel, said pull tube having ports therein opening into said pumping chamber, and a check valve mounted 30 on the upper end of the traveling barrel, and closure means between the tubing and the stationary barrel, said closure means being arranged below the bottom discharge valve.

35. 8. A duplex pump for wells, a tubing in which the pump is positioned comprising a standing valve, a locking shoe depending from the standing valve, said locking shoe being releasably held in the tubing, a bottom discharge valve housing fixedly mounted on the standing valve and arranged above said standing valve, a valve in said housing, said housing having ports opening into the tubing, said valve controlling the flow from within the pump to said ports, a stationary barrel mounted on the standing valve and rising therefrom, a stationary pull tube mounted on said housing and rising therefrom, a stationary piston mounted on the upper end of the pull tube, a traveling barrel extending over the stationary piston and arranged within the stationary barrel, a traveling piston mounted on the lower end of the traveling barrel, said traveling piston surrounding the pull tube, said pump having a lower pumping chamber below the traveling piston and within the stationary barrel, said pull tube having ports therein opening into said pumping chamber, and a check valve mounted 40 on the upper end of the traveling barrel, and closure means between the tubing and the stationary barrel, said closure means being arranged below the bottom discharge valve.

45. 9. A duplex pump for wells, a tubing in which the pump is positioned comprising a standing valve, a locking shoe depending from the standing valve, said locking shoe being releasably held in the tubing, a bottom discharge valve housing fixedly mounted on the standing valve and arranged above said standing valve, a valve in said housing, said housing having ports opening into the tubing, said valve controlling the flow from within the pump to said ports, a stationary barrel mounted on the standing valve and rising therefrom, a stationary pull tube mounted on said housing and rising therefrom, a stationary piston mounted on the upper end of the pull tube, a traveling barrel extending over the stationary piston and arranged within the stationary barrel, a traveling piston mounted on the lower end of the traveling barrel, said traveling piston surrounding the pull tube, said pump having a lower pumping chamber below the traveling piston and within the stationary barrel, said pull tube having ports therein opening into said pumping chamber, and a check valve mounted 50 on the upper end of the traveling barrel, and closure means between the tubing and the stationary barrel, said closure means being arranged below the bottom discharge valve.

55. 10. A duplex pump for wells, a tubing in which the pump is positioned comprising a standing valve, a locking shoe depending from the standing valve, said locking shoe being releasably held in the tubing, a bottom discharge valve housing fixedly mounted on the standing valve and arranged above said standing valve, a valve in said housing, said housing having ports opening into the tubing, said valve controlling the flow from within the pump to said ports, a stationary barrel mounted on the standing valve and rising therefrom, a stationary pull tube mounted on said housing and rising therefrom, a stationary piston mounted on the upper end of the pull tube, a traveling barrel extending over the stationary piston and arranged within the stationary barrel, a traveling piston mounted on the lower end of the traveling barrel, said traveling piston surrounding the pull tube, said pump having a lower pumping chamber below the traveling piston and within the stationary barrel, said pull tube having ports therein opening into said pumping chamber, and a check valve mounted 60 on the upper end of the traveling barrel, and closure means between the tubing and the stationary barrel, said closure means being arranged below the bottom discharge valve.

65. 11. A duplex pump for wells, a tubing in which the pump is positioned comprising a standing valve, a locking shoe depending from the standing valve, said locking shoe being releasably held in the tubing, a bottom discharge valve housing fixedly mounted on the standing valve and arranged above said standing valve, a valve in said housing, said housing having ports opening into the tubing, said valve controlling the flow from within the pump to said ports, a stationary barrel mounted on the standing valve and rising therefrom, a stationary pull tube mounted on said housing and rising therefrom, a stationary piston mounted on the upper end of the pull tube, a traveling barrel extending over the stationary piston and arranged within the stationary barrel, a traveling piston mounted on the lower end of the traveling barrel, said traveling piston surrounding the pull tube, said pump having a lower pumping chamber below the traveling piston and within the stationary barrel, said pull tube having ports therein opening into said pumping chamber, and a check valve mounted 70 on the upper end of the traveling barrel, and closure means between the tubing and the stationary barrel, said closure means being arranged below the bottom discharge valve.

75. 12. A duplex pump for wells, a tubing in which the pump is positioned comprising a standing valve, a locking shoe depending from the standing valve, said locking shoe being releasably held in the tubing, a bottom discharge valve housing fixedly mounted on the standing valve and arranged above said standing valve, a valve in said housing, said housing having ports opening into the tubing, said valve controlling the flow from within the pump to said ports, a stationary barrel mounted on the standing valve and rising therefrom, a stationary pull tube mounted on said housing and rising therefrom, a stationary piston mounted on the upper end of the pull tube, a traveling barrel extending over the stationary piston and arranged within the stationary barrel, a traveling piston mounted on the lower end of the traveling barrel, said traveling piston surrounding the pull tube, said pump having a lower pumping chamber below the traveling piston and within the stationary barrel, said pull tube having ports therein opening into said pumping chamber, and a check valve mounted 75 on the upper end of the traveling barrel, and closure means between the tubing and the stationary barrel, said closure means being arranged below the bottom discharge valve.

the pump is positioned comprising a standing valve, a locking shoe depending from the standing valve, said locking shoe being releasably held in the tubing, a bottom discharge valve housing 5 fixedly mounted on the standing valve and arranged above said standing valve, a valve in said housing, said housing having ports opening into the tubing, said valve controlling the flow from within the pump to said ports, a stationary barrel mounted on the standing valve and rising therefrom, a stationary pull tube mounted on said housing and rising therefrom, a stationary piston mounted on the upper end of the pull tube, 10 a traveling barrel extending over the stationary

piston and arranged within the stationary barrel, a traveling piston mounted on the lower end of the traveling barrel, said traveling piston surrounding the pull tube, said pump having a lower pumping chamber below the traveling piston and within the stationary barrel, said pull tube having ports therein opening into said pumping chamber, a check valve mounted on the upper end of the traveling barrel, and a check valve mounted on the upper end of the stationary 10 piston, and closure means between the tubing and the stationary barrel, said closure means being arranged below the bottom discharge valve.
